FIG. I.

FIG. 2.

To all whom it may concern:

Be it known that we, Peter Altman, Laurence D. Bakke, and Richard T. Robinette, all citizens of the United States and residents, respectively, of Detroit, Plymouth, and Detroit, in the State of Michigan, have invented a new, original, and ornamental Design for an Internal Combustion Engine, of which the following is a specification, reference being had to the accompanying drawing, forming a part thereof.

Fig. 1 is a perspective view showing one end and one side of an internal combustion engine embodying our new design; and

Fig. 2 is a perspective view of the same showing the other end and side thereof.

We claim:

The ornamental design for an internal combustion engine, as shown.
